UNITED STATES PATENT OFFICE.

OSCAR M. PANNIER, OF PITTSBURGH, PENNSYLVANIA, ASSIGNOR TO PANNIER BROTHERS STAMP COMPANY, OF PITTSBURGH, PENNSYLVANIA, A CORPORATION OF PENNSYLVANIA.

STAMP.

1,079,061.

Specification of Letters Patent. Patented Nov. 18, 1913.

Application filed April 14, 1913. Serial No. 760,882.

To all whom it may concern:

Be it known that I, OSCAR M. PANNIER, a citizen of the United States, residing at Pittsburgh, in the county of Allegheny and 5 State of Pennsylvania, have invented certain new and useful Improvements in Stamps, of which the following is a specification.

My invention is an improvement in the 10 class of stamps, similar to rubber stamps, and adapted to mark any suitable surface with an imprint by means of raised letters extending beyond the supporting base or surface, a series of such being removably 15 mounted upon a supporting framework, suitably curved to provide for a rolling or rocking action of the device as used by the operator.

The invention has in view to provide a 20 stamp of this character for hand use, in connection with a suitable inking pad.

The principal object of the invention is to provide in a device of this character, a manipulable base having a curved supporting 25 and attaching bottom, preferably slightly resilient, adapted to receive the several removable and attachable units, the base and printing units being constructed and adapted for easy and quick changing of the units, 30 and for fixedly holding them upon the base, the printing units also being constructed in a novel manner for facilitating the carrying out of their desired function, in the manner more fully hereinafter described.

35 In the drawings illustrating preferred forms of the invention, Figure 1 is an under plan view of the stamp showing a portion of its length provided with printing units. Fig. 2 is a view of the device in side elevation. Fig. 3 is a cross section taken on the line III. III. of Fig. 2. Fig. 4 is an enlarged longitudinal sectional view of one of the units, detached. Fig. 5 is a perspective view of one of the units partly broken away. 45 Fig. 6 is a partial plan view showing a modified construction of attaching base.

The attaching base 2 of the device, as shown in the principal figures of the drawing, is formed of a longitudinal strip or 50 piece of sheet metal of sufficient gage and stiffness to maintain its form with sufficient resilience to provide ample cushioning action and application to the surface to be stamped, the strip 2 being deflected at each 55 end providing terminals 3, 3, which are secured to the end portions of a holding and

operating handle member 4. Said handle member, as shown, is a wooden bar to which the ends 3 of the strip 2 are secured in any suitable manner, as by connecting screws 5, 60 although any suitable handle structure may be employed, whereby to effect the desired functions. At suitable intervals longitudinally of the strip 2, the opposite edge portions are cut or slit transversely for a short 65 distance inwardly at each side providing recessed openings 6 with intervening outwardly projecting edge portions 7.

The partly severed edge portions of the strip corresponding to the openings 6 are 70 bent inwardly underneath the strip 2 at each side, as indicated at 8, the recessed edge portions of the strip thus being rounded, as indicated at 9, providing finished edges for attachment of the terminal lip portions of 75 the printing or stamping units A. The inwardly bent lips 8 also serve to stiffen or reinforce the edge portions, thereby enabling lighter metal to be used, if desired, with the accompanying advantage of reducing the 80 cost and weight. By bending these parts inwardly, I avoid any projecting parts beyond the outer face of the base.

The several units A are composed of a body portion a of rubber or other suitable 85 material which is molded around a sheet metal core portion 10 in such a manner as to be firmly and permanently incorporated therewith. For such purpose the sheet metal core 10, which is of a flat strip 11, is provided throughout its middle portion with a plurality of closely adjacent transverse 90 openings 12.

The rubber stamping unit is made by molding the rubber entirely around both 95 sides and edges of the metal core for the main portion of its length, the rubber extending integrally through the openings 12, filling them, as indicated at 13, and intimately binding the opposite side portions 100 together and fixedly securing the rubber and metal immovably together. One end portion of the metal core 11 is bent inwardly forming the angular lip 14 and adapted to engage around one of the rounded edges 9 between 105 the projections 7 at one side of the strip 2, the other end portion of the core being similarly bent inwardly, as indicated at 15, for the same purpose. The several stamping units are thus held individually in position, 110 longitudinally of the base 2. As shown, the core or base 11 of the stamping unit is pro-

vided with an outwardly deflected extended finger clip 16, for attaching or detaching the unit. The rubber body portion of the rubber stamping member A is provided at the side 5 opposite such holding elements with the outwardly projecting character or numeral α' , as will be readily understood.

In use, the several units are applied to the strip or base 2 in proper arrangement to define 10 a word by letters, or a series of printing numerals for stamping a number, each unit being sprung over the rounded edge portions 9, the angular inwardly deflected lips 14, 15, binding the unit inwardly against the outer face of the strip 2, bringing the inner 15 face of the rubber unit into close intimate contact therewith. In removing the device, the finger clip 16 is pressed upwardly, releasing that end of the unit, whereupon it 20 may be readily removed for substitution of another.

When desired, the curved holding base may be formed to provide a plurality of rows of unit attaching portions 2', 2'', as 25 in Fig. 6, the space or spaces 6'' between the outermost spaces 6', and in cross alinement therewith, being formed by slitting the metal crosswise and lengthwise to provide inwardly turned lips 8', 8'', shown in dotted 30 lines, forming similar rounded holding edges, as described, and spaces of ample width to receive the adjacent holding terminals of a plurality of rows of stamping units. With such construction, the finger of 35 the operator may be readily extended inwardly underneath the base, and each particular unit released at will. With either construction I provide for positive and easy attachment and detachment of the stamping 40 units and prevention of movement longitudinally of the curved base 2, by means of the lateral alternating projections and recesses on the holding base and the co-acting terminals of the metal core 11 of the stamping unit.

It will be understood that the size, design, arrangement, proportions or other details of the invention may be readily changed or modified by the skilled mechanic to suit 50 special conditions of use, and that the invention may be varied in different ways to provide for any special arrangement or application of the stamping elements, but all such changes are to be considered as within the 55 scope of the following claims.

What I claim is:

1. In a stamp, the combination of a holding handle, a resilient outwardly curved sheet metal base secured to each end of the 60 handle and arched away therefrom provided with laterally extending integral projections and intervening recesses, and removable stamping units having clip portions for engagement therewith, substantially as set forth.

2. In a stamp, the combination of a holding handle, a resilient outwardly curved sheet metal base secured to each end of the handle and arched away therefrom provided with laterally extending integral projections 70 and intervening recesses, and removable stamping units having terminal inwardly turned sheet metal clip portions for engagement therewith, substantially as set forth.

3. In a stamp, the combination of a holding handle, a resilient outwardly curved sheet metal base secured to each end of the handle and arched away therefrom provided with laterally extending integral projections 75 and intervening recesses, and removable stamping units having an embedded sheet metal strip extending from one end and inwardly turned for engagement with one edge of said base and extending from the other end and inwardly turned for engagement with the other edge of said base and provided with an outwardly deflected finger terminal, substantially as set forth.

4. In a stamp, the combination of a holding handle, a resilient outwardly curved 90 sheet metal base secured to each end of the handle and arched away therefrom provided with inwardly severed lateral tongues bent inwardly upon the base between alternating projecting spacing tongues, and removable 95 stamping units having interfitting clip portions for engagement therewith, substantially as set forth.

5. In a stamp, the combination of a holding handle, a resilient outwardly curved 100 sheet metal base secured to each end of the handle and arched away therefrom provided with inwardly severed lateral tongues bent inwardly upon the base between alternating projecting spacing tongues and providing 105 rounded bearing edges, and removable stamping units having interfitting clip portions for engagement therewith, substantially as set forth.

6. In a stamp, the combination of a holding handle, a resilient outwardly curved sheet metal base secured to each end of the handle and arched away therefrom provided with inwardly severed lateral tongues bent inwardly upon the base between alternating 115 projecting spacing tongues and providing rounded bearing edges, and removable stamping units consisting of a rubber body portion and a sheet metal base portion embedded in the rubber and provided with projecting terminal clip portions adapted to removably engage the rounded edges of the inwardly bent severed tongues, substantially as set forth.

7. In a stamp, the combination of a holding handle, a resilient outwardly curved sheet metal base secured to each end of the handle and arched away therefrom provided with transversely slitted inwardly turned 125 portions providing rounded edges and cavi- 130

- ties between alternating integral spacing portions, and removable stamping units having clip portions for engagement therewith, substantially as set forth.
5. 8. In a stamp, the combination of a holding handle, a resilient outwardly curved sheet metal supporting base secured to each end of the handle and arched away therefrom, removable stamping units mounted on
- 10 said base each consisting of a rubber body portion and a sheet metal base portion embedded in the rubber and having projecting attaching terminal portions, the edges of the sheet metal supporting base being provided
- with alternating projections and recesses, the 15 terminal portions of the unit base engaging with the projections and recesses of the supporting base, thereby providing interfitting edge-engaging holding portions adapted to effect and facilitate attachment, detachment 20 and fixed spacing of the individual stamping units, substantially as set forth.

In testimony whereof I hereunto affix my signature in the presence of two witnesses.

OSCAR M. PANNIER.
